UNITED STATES PATENT OFFICE.

JAMES T. COWLEY, OF SCITUATE, MASSACHUSETTS, ASSIGNOR TO THE LAMSON COMPANY, OF BOSTON, MASSACHUSETTS, A CORPORATION OF NEW JERSEY.

PNEUMATIC AMMUNITION-CONVEYING SYSTEM.

1,148,082.

Specification of Letters Patent. Patented July 27, 1915.

Application filed June 30, 1913. Serial No. 776,500.

To all whom it may concern:

Be it known that I, JAMES T. COWLEY, a citizen of the United States, residing at Scituate, in the county of Plymouth and State of Massachusetts, have invented certain new and useful Improvements in Pneumatic Ammunition-Conveying Systems, of which the following is a specification.

This invention relates to a pneumatic ammunition conveying system of that class used for conveying both a projectile and powder or the like from the handling-room of a magazine to the guns, preferably through a single tube. Systems of this 10 character comprise a tube or conduit through which the charge is pneumatically propelled from the handling-room to a point near the guns to be served; the tube being provided with a sending terminal at the magazine or 15 handling-room end thereof, and having a delivery terminal preferably at its outer extremity adjacent to the broadside or other guns to which the charge is to be delivered; the system also having means for admitting 20 compressed air to the sending terminal behind the charge to be conveyed.

The invention herein described relates more particularly to certain improvements in a system of this character whereby not 30 only may a charge be expeditiously and safely despatched from the magazine, but further the removal thereof from the conveying apparatus by the operatives stationed at the delivery terminal is facilitated.

A further object of the invention is to control the progress of the charge during its advance through the tube, whereby to insure greater safety in handling the explosive materials conveyed and reduce injurious stresses, imposed upon the conveying apparatus while the charge is in transit, substantially to a minimum.

It is further aimed herein to automatically separate the shells or projectiles from the cases containing the powder, or other explosive material, at the delivery terminal by means of such a simple and effective construction that the likelihood of the system becoming deranged at this point, as may happen when a considerable number of movable elements are involved in the separating means, is practically eliminated.

A further object of the invention is to so 55 construct the delivery terminal that suc-

ceeding charges may follow each other through the tube relatively closely, this terminal having provisions whereby the powder case, for example, of a preceding charge is automatically removed from the path of 60 the shell and case of a succeeding charge. In like manner the shells are brought to rest in positions where they, like the powder cases, may be most easily removed from the apparatus, while at the same time a 65 previously delivered shell automatically so positions itself as not to be subject to injury by a succeeding shell, or vice versa.

These and other objects of my invention will be hereinafter more fully set forth and 70 the novel elements and combinations of elements whereby said objects may be attained will be more particularly pointed out in the claims appended hereto.

In the accompanying drawings I have 75 exemplified a preferred system of the type in question, together with a modification of the delivery terminal which, in certain cases, may be used in lieu of the delivery terminal shown in the general assembly.

I am aware, however, that many other changes and modifications may be made in the system without departing from the spirit of my invention, and I hence desire to be limited only by the scope of the ap- 85 pended claims.

In the several figures like characters of reference designate like parts.

Referring to the drawings: Figure 1 is a somewhat diagrammatic representation of 90 the preferred system, viewed in elevation. Fig. 2 is a detail vertical section of the despatching valve shown adjacent the terminal in the lower part of Fig. 1; the section being taken in the plane of the paper. Fig. 3 is a 95 detail transverse section taken on line III—III of Fig. 1. Fig. 4 is a similar section taken on line IV—IV of Fig. 1. Fig. 5 is a detail elevation, partly in section, of the despatching terminal; pipe connections being herein shown which for convenience of illustration have been omitted from Fig. 1. Fig. 6 is a transverse vertical section of the terminal shown in Fig. 5; the section being taken on line VI—VI. Fig. 7 is a view 100 105 similar to Fig. 6, but showing the terminal cover in its closed position. Fig. 8 is a detail section taken on line VIII—VIII of Fig. 5. Fig. 9 is a detail vertical transverse section taken on line IX—IX of Fig. 5. 110

Fig. 10 is an elevation of the delivery terminal shown in Fig. 1, drawn to an enlarged scale. Fig. 11 is a plan view of said delivery terminal; a portion of the frame of the latter being broken away. Fig. 12 is a vertical transverse section of said terminal taken on line XII—XII of Fig. 11. Fig. 13 is an elevation of a modified form of the delivery terminal. Fig. 14 is a plan of the 10 same, and Fig. 15 is a transverse section taken on line XV—XV of Fig. 13.

The sending terminal has been broadly designated A and the transmission tube B leads therefrom to the delivery terminal C, 15 the latter being preferably unprovided with a cover while the former has hinged at 1—1 to the body or casing 2 thereof, a cover 3. This casing is extended forwardly to provide a slightly concaved shelf 4 upon which 20 the charge, consisting of the shell D and a powder case E together with the piston or pusher F, may be laid, preparatory to inserting it into the terminal. Suitably journaled above the casing 2 is a rock-shaft 5 which carries at one end an arm 6 and at 25 the other a triangular member 7; a pair of links 8 respectively connecting the extremities of members 6 and 7 to the cover so that a pair of toggles are provided, adapted when 30 the respective joints thereof are in alignment to hold the cover firmly closed. Links 9 connect the third corner of the member 7 with the depending rod of a piston 10, reciprocably mounted in a cylinder 11, sup- 35 ported from a hollow upright 12 disposed at the forward end of terminal A. A high pressure supply pipe 13 is connected by pipes 14 and 15, and port 16 in the wall of the cylinder 11, with the space in the latter 40 below the piston when the latter is in its upper position, whereby the cover 3 is normally held open. The rear end of the terminal is closed by a suitable cap 17, an extension 18 of which supports the outer end 45 of the shaft 5, and the forward end is normally closed by a gate-valve 19 which rides in grooves 20 in the upright 12. Valve 19 is pneumatically operated through the intermediacy of a piston 21 disposed in a cylinder 50 22 also carried by said upright; the chamber in the cylinder above the piston 21 being normally in communication with pipe 13 through a pipe 23 and chamber 24 in the casing 25 of the despatching valve 26. The 55 latter is preferably cupped to receive a spring 27 which tends to hold it in its lower position in which pipes 13 and 23 are in free communication, but in which position also communication between pipe 13 and a 60 pipe 28, leading to the upper end of cylinder 11, is cut off. A valve stem 29 extends upwardly from valve 26 through the cap 30 of casing 25, and to this cap is pivoted an operating lever 31 having a slotted connection with a head 32, pinned to the upper end

of said stem 29. The lower end of this valve stem is preferably enlarged and extends downwardly as shown in Fig. 2; a groove 33 immediately below the valve being adapted for the reception of a locking-pin 34 when 70 the valve is in its lower position, while the lower extremity of the stem correspondingly may rest upon this pin when the valve is in substantially its uppermost position and when said pin is projected against the action of its spring 35 into the path of the valve stem, in the manner hereinafter described. Mounted upon a shaft 36 journaled in the casing 37 which supports the valve and locking-pin parts, is a latch 38, the free 80 end of which is also adapted to be moved in, by a spring 39, under the lower extremity of the valve stem 29 when the valve is in its upper position; and a trip arm 40, keyed to this shaft projects down through a slot 85 41 in the tube B, when the latch is so disposed; as indicated by dotted lines in Fig. 2. The rear end of spring 39 is affixed to a pivoted stop 42, which, when the stem 29 is located in its lower position, is pressed 90 down by said stem against the action of the spring 39, while, when the stem is raised the free end of this stop engages latch 38 immediately below its in-bent free end and limits the inward movement of said latch. 95

Assuming now that a charge has been placed within the body of the sending terminal, the pointed end of the shell D being nearest the transmission tube, the powder case E being directly behind the shell and the pusher F being to the rear of the powder case (the relative positions of these articles being shown in the portion of the tube broken away in Fig. 1). The lever is now thrown to the right, raising valve 26 and thereby closing communication between the pipe 13 and the space above the piston 21, while also exhausting the air in said space through the port 43 below said valve. Simultaneously air under pressure flows 100 through pipe 28 into the recess 44 in the upper end of cylinder 11 and thence flows past the check valve 45 in the piston head; more than counterbalancing the pressure upon the under side of said piston since the air there beneath, and any which enters through port 16, escapes through port 46 in the lower extremity of the cylinder and thence through a pipe 47 to the space above piston 21, which, as previously noted, is at such time in communication with the atmosphere via port 43. The descent of piston 10 closes and ultimately toggle-locks the cover 3; but the fall of the cover is checked by the cushion formed by the air trapped below this piston after it closes the port 46 by its passage thereover. When piston 10 has reached substantially its lowermost position, so that the cover is held securely closed, it uncovers ports 16, 110 permitting the air entering cylinder 11 115

through pipe 28 to pass thence through pipe 15 to a recess 48 in the bottom of cylinder 22 and past a check valve 49 into the space below piston 21; elevating the latter and thereby lifting the gate-valve 19.

The upright 12 is hollow and the conduit 50 therein receives air from a low pressure supply pipe 51; which conduit is at all times in communication with the tube B, 10 through which a current of air normally always flows in the direction indicated by the full line arrows.

The casing 52 which closes the forward side of conduit 50 near its lower end is 15 shaped as shown in Figs. 5 and 9 to provide pockets 52', and the base of the upright 12 is cored out to form a U shaped channel 51 around the central circular opening 53 through which the charge emerges when 20 gate-valve 19 is raised. Apertures 53' in the respective front side walls of the channel 51 provide for communication between conduit 50 and said channel; but air can only flow through these openings when the 25 gate-valve 19 has been raised sufficiently to uncover openings 53'; laterally disposed ports 54 being provided in valve 19 for this purpose.

The low pressure air then flows through 30 channel 51 and the conduit or duct 55 into the cavity 56 in the cap 17, and from thence into the terminal chamber to the rear of the charge, transmitting member or piston F; driving the latter together with the charge 35 in front of it past the now fully opened valve 19 and into the tube B, toward the delivery terminal.

It may be here noted that the valve 26 had meanwhile been held in position to effect the actions above described by the inward movement of the latch or dog 38, the 40 moment that the valve stem was elevated sufficiently to clear this member. Correspondingly the trip arm or lever 40 had been, at such time, rocked down some distance into the transmission tube.

The shell D is of relatively small diameter and reposes upon the bottom of the tube so that the top thereof clears this lever 40 50 by a considerable distance when driven forward through the tube. The powder case E, is also of smaller diameter than the inside of the tube and correspondingly clears lever 40. Piston F is, however, of substantially the same diameter as the inside of the tube and when it encounters lever 40, it raises the latter and thereby frees valve stem 29, which is immediately driven down by spring 27, closing port 43, opening pipe 55 28 again to the atmosphere; air escaping from the upper end of cylinder 11 through this pipe and a port 57 in cap 30; while live air is again admitted to the upper end of cylinder 22 through pipe 23.

65 The air entering the lower part of cylin-

der 11 through pipe 15 can no longer escape and raises piston 10, breaking the toggles which lock cover 3 closed, and raising said cover preparatory to the insertion of a second charge.

In pipes 13, 14, 23, 28 and 47 are throttle valves 58, 59, 60, 61, 62 and 63 which serve to regulate the flow of air to the several parts to be actuated. Around the throttle 62, however, in pipe 28, is a by-pass 64 in 70 which is a check valve 65, so that valve 62 does not oppose the free upward movement of piston 10 but does affect the speed of its downward or cover closing movement. As the cover is raised the piston 21 descends, 75 closing the gate-valve 19; air being first admitted to the upper side of this piston past a check valve 65' while the air below the piston is driven back into the high pressure line by the weight of said piston and 80 valve 19.

It will be observed that piston 21 is cushioned by air trapped therebeneath when nearly at the end of its downward movement; 85 ports through which the air below this piston escapes to pipes 15, 14 and 13, being located somewhat above the bottom of the piston when in its lowermost position, like the port 46 in cylinder 11.

In both cylinder 11 and cylinder 21, provision is made for insuring an adequate cushion of air below the respective pistons to check their downward movement. To this end cylinder 22 has a port 67 therein, preferably above the level of the port 68' 90 which opens into pipe 47; and a conduit leads from this port 67 to a recess in which is disposed a spring pressed check valve 69. When the piston 21 has descended just far enough to uncover port 67, the compressed 95 air above the piston raises valve 69 and passing thence through port 70, temporarily equalizes the pressure upon the respective sides of the piston. Immediately after this, however, the piston covers port 70 and the 100 air trapped below said piston, being already under considerable pressure, serves as an effective cushioning medium. In like manner cylinder 11 is provided with a port 67', valve 69' and port 70' which co-act with 105 piston 10 to effect a like result. In both of these cylinders, also, air is admitted in augmented quantity as the respective pistons are being raised. For example, in cylinder 11, air first raises check valve 66 and thereafter is more freely admitted when the piston 110 successively uncovers ports 46 and 16.

Similarly when piston 21 is being raised, valve 49 first opens and thereafter the piston successively uncovers ports 68' and 68 and 115 reversely covers these ports, aiding in cushioning piston 21 when the latter descends.

As shown in Figs. 5, 6 and 7, the gate valve 19 is slotted at 71, partly for the purpose of clearing the boss in which valve 69 120

is disposed and partly to afford a free passage of air from conduit 50 into the tube, at all times. It has further been found desirable, however, to provide a by-pass 72 in order to insure an adequate flow of air through tube B to propel a preceding charge while a succeeding charge is being despatched, and a throttle 73 in a diaphragm 74 located in this by-pass permits of the adjustment of this flow of air to a nicety.

The trip actuated lock for the operating valve 26 provides means for insuring the proper despatch of a charge from the despatching terminal before any further operation of the controlling or operating valve can be effected; so that after the cover has once been closed and the gate-valve opened, no change in the position of these parts can occur until the trip is engaged by the piston or pusher of the charge being despatched, and both the projectile, or shell, and its powder case, which together constitute the charge proper, must obviously always be well within the tube before the pusher therebehind actuates the trip. It is hence practically impossible to inadvertently close the gate-valve upon, let us say, the case of powder or other explosive material, which action might result disastrously. In addition, however, it has also been found desirable to insure a proper spacing of charges in transit without undue loss of time, as is the case where one charge must be delivered to the receiving terminal before a second can be despatched. The means by which charges may be spaced apart while yet permitting a plurality of charges to be in course of transit simultaneously through the transmission tube will accordingly now be described.

The locking-pin 34, above referred to, has mounted upon the forward or outer extremity thereof a piston 74 which is reciprocable in a cylindrical pocket 75 in the casting 76 within which rides said pin 34. The spring 35 normally holds this piston and pin in their outermost positions; the pin being then clear of stem 29. The cylinder 75 has a head or cap 78 to which is attached a pipe 79 which leads into tube B a short distance beyond the trip casing 37. A second pipe 80, connects the inner end of cylinder 75 with a point 81 in the tube relatively remote from the despatching terminal.

When the air flows freely through the tube the pressure therein is not sufficient to overcome the spring 35, but when a charge is being propelled from terminal A, as soon as its piston clears the mouth of pipe 79, air under pressure sufficient to compress spring 35 enters the chamber 82 within cap 78 and drives piston 74 together with pin 34 inwardly, which enters the point of the pin into groove 33; stem 29 being at such time in its lower position. Thereafter, until the

piston F of the charge has passed the point 81, the operating lever 31 cannot be moved so that the cover 3 must remain open, preventing the despatch of a succeeding charge for a substantially determined interval of 70 time. When, however, the first charge with its piston has passed this point, air under pressure is admitted to pipe 80 and counterbalances the pressure in chamber 82, enabling spring 35 to retract the pin and free the despatching valve. If, by any chance, immediately after the instant that the piston of a first charge operates the trip lever 40 releasing valve 26, said valve should be raised before the piston uncovers the mouth of pipe 79, then when pin 34 is driven in by its piston 74, in manner aforesaid, it will latch up the valve stem by engaging the lower end thereof; holding valve 26 in position to maintain the cover closed until the charge passes point 81 in the tube, after which the locking pin is automatically withdrawn, valve 26 descends and the cover 3 again opens.

It is frequently necessary to provide relatively sharp bends in the transmission tube and to avoid unnecessary wear and tear upon the apparatus means have been provided in such cases for reducing the speed of the charge as it approaches and while it traverses the bend. In the exemplification shown in Fig. 1 a connection 83 consisting of a pair of clamping members or straps connected together by bolts, as shown in Fig. 3, is affixed to the tube B some distance below the bend 83' therein and a corresponding structure is mounted upon the tube immediately beyond this bend. The tube is perforated as at 84 at each of these points and one of the straps is recessed as at 85 to afford communication between a pipe 86, which is connected to this element, and the tube B, through these perforations.

Pipe 86 virtually forms a by-pass around the bend 83' whereby a certain amount of the air, to the rear of the piston propelling a charge up the tube, is able to escape around back into the tube ahead of the charge; thus materially reducing the propulsive effort exerted upon said piston. It is advisable to provide a throttle valve 87 or the like in this by-pass 86 so as to provide means for adjusting the speed of the charge when passing around the bend. As the charge approaches the delivery terminal C it is also desirable to again check the speed thereof so that it may not enter the delivery terminal under too great momentum. To this end valve casings 88, of which any suitable number may be provided, are inserted in, or adjacent to, the bend 89 in the upper portion of the pipe. As shown in Fig. 4 these valves consist of tubular sections provided with flanges 90 to which the flanges of the adjacent pipe sections may be 130

bolted; said sections each being apertured upon one side thereof as at 91 and having a grating 92 across this aperture so that the charge may pass freely thereover while the 5 compressed air to the rear thereof escapes in part at least through the said grating. The opening 91 in the side of each of these sections is normally closed by a valve 93 which is held upon its seat by means of a 10 suitable compression spring 94; the outer extremity of this spring bearing against the hub of a spider 95 at the mouth of the aperture 91; and the other extremity of said spring bearing against the head of a bolt 96 15 which extends outwardly through the spider and valve. Outward movement of this valve may be adjustably limited by means of a set-screw 97 mounted in a yoke 98 attached to the outer side of the flange of the spider. 20 Obviously the spring 94 may be given any desired tension by screwing down the nut of the bolt 96 and in practice it is desirable to have the spring of the valve 88, which is first encountered by a charge, under greater 25 compression than that of the subsequently encountered valve; so that when passing the lower or first of these valves the air behind the pusher or piston of a given charge escapes only to a moderate extent; but immediately 30 thereafter, as the piston passes over the grating 92 of the second valve, a much larger proportion of the compressed air escapes to the atmosphere; the charge hence being delivered smoothly and comparatively 35 gently to the delivery terminal.

Referring now more particularly to Figs. 10, 11 and 12, the preferred delivery terminal consists substantially of but a single member which comprises a semi-tubular 40 portion 99 which is flared out at the under side thereof to form a sloping shelf 100. The shell D as it emerges from the tube B is guided around by the curved tubular portion 99 until the point thereof strikes a 45 bumper 101 which is located in a nearly rectangular bend 102 in the more remote end of the portion 99. The shell, however, does not come to rest at this point owing to the slope of the shelf which sustains it; but 50 rolls or swivels downwardly, the butt end moving through an arc of greater radius than the point of the shell until it ultimately comes to rest against the flange-like extremity 103 of the portion 99. The shell 55 may then be drawn end-wise out of the terminal as indicated by the shell shown in dotted lines and designated D'.

It is evident that if a succeeding shell D be delivered to the terminal before the preceding shell D' has been removed therefrom, no harmful collision can result since shell D' after it strikes the bumper 101 has ample time wherein to roll itself around against the flange 103 before the succeeding shell 60 65 encounters this bumper. Thereafter the

shell D will merely roll around in like manner until it comes to rest in the terminal substantially side by side with the preceding shell D'; and if the latter be withdrawn shell D will then roll down into the position 70 occupied by the shell just removed.

Projecting inwardly from the inner extremity of the semi-tubular portion 99 is a powder case bumper 104 which consists preferably of a cup 105 within which is a 75 spring 106, the inner extremity of which bears against the head of a bolt 107 which projects through the bottom of the cup and the extremity of which is shouldered and threaded for engagement with a nut 108 80 which holds it firmly in position in the terminal casing. The other extremity of the spring 106 bears against a suitable closure 109 for the cup 105; which closure is recessed to firmly hold the bumper proper 104 85 therein.

Bumpers 101 and 104 may be of any suitable material which is reasonably resilient and which should be adapted to withstand the rough usage to which these parts are 90 subjected. As best shown in Fig. 12 the bumper 104 is disposed at a sufficient elevation within the terminal casing to enable a shell to pass freely thereunder; but since the powder cases are of greater diameter 95 than the shells the forward extremity of the powder case of each charge will encounter the bumper 104 and be thereby substantially brought to rest; the case thereafter merely rolling down the inclined shelf 100 until it encounters a flange 110. To insure the end of the powder case striking fairly upon the bumper 104 the interior of the semi-tubular portion is ribbed as at 111; this rib holding the powder cases out somewhat, away from the interior wall of the terminal, and bringing the centers of their forward ends nearly in alignment with the center of the bumper 104. The pusher behind the charge also rolls down the shelf 110 and may be conveniently removed from the portion 112 thereof at which the powder cases are withdrawn.

The shelf is preferably of sufficient width to permit of at least one additional powder 115 case being delivered against the bumper 104 after a preceding case has come to rest against the flange 110.

It will hence be seen that by means of a terminal having practically no movable 120 parts, if we disregard the bumper 104, the shells may be effectively separated from their accompanying powder cases, while owing to the peculiar construction of the terminal, successive charges may be delivered thereto and the shells and cases of such charges will be automatically so positioned as to eliminate possible injury thereto by succeeding charges.

In Figs. 13, 14 and 15 I have shown a 125

modification of this terminal which, like the former, comprises a semi-cylindrical portion 99' and a shelf 100'; the latter in the present instance being substantially 5 horizontal rather than inclined. In the former case gravity was depended upon to cause the shells and powder cases to dispose themselves in positions from whence they could be conveniently removed. In the 10 modified terminal, however, the shell passes out of the tube B and continues on, by its momentum, over the floor of the shelf and beneath a shoe 113, the function of which will be hereinafter referred to.

15 As shown in Fig. 13, a short downward slope in the surface of the otherwise horizontal shelf, occurs between the points 114 and 115 and the relatively slowly moving shell slides down this slope onto the flat 20 portion 116 of the floor of the casing; the shell bringing up against a bumper 117 and being conveniently positioned for removal through the opening 118 between the bumper 117 and a short flange 119.

25 Again, in this case as in the former, the difference in diameter of the shell and powder case is taken advantage of to effect a separation of one from the other, so that while the relatively small diametered and 30 short shell is able to pass freely through the terminal until it comes to rest against its bumper at the outer extremity thereof, the relatively long and somewhat larger diametered powder case cannot tilt around the 35 edge 114 to slide down the short incline, but remains horizontally disposed upon the floor of the terminal and slips under the shoe 113; which latter frictionally engages the upper side of the powder case until the forward 40 end of said case impinges against a bumper 120.

The under surface of the shoe 113 is arched and hence holds the powder case against lateral displacement. This shoe is 45 yieldingly mounted upon a pair of arms 121; springs 122 being interposed between the said arms and the heads of the bolts 123 which suspend the shoe from said arms. These arms are fixedly mounted upon a rock 50 shaft 124 journaled in suitable brackets 125—125' upon the outside of the terminal casing; and kick-off arms 126, preferably integrally connected to the arms 121, extend downwardly and inwardly around the side 55 of the casing as indicated in Fig. 15 so that the toes 127 of these members project into apertures 128 in the rear wall of said casing, but normally not through said apertures sufficiently to impede the progress of 60 a powder case therewith. A crank 129 mounted upon the inner end of the rock shaft 124 is connected by means of a link 130 with a foot lever or treadle 131 pivoted to the casing as at 132.

65 When it is desired to remove a powder

case from the casing, which is preferably immediately after the arrival thereof, the operator pushes down the treadle 131 with his foot and thereby rocks the shaft 124, raising the shoe 113 from the powder case 70 and simultaneously projecting the toes 127 of the kick-off levers through the apertures 128 and against the wall of the powder case, rolling it out of the path of travel of a succeeding case; the so displaced case 75 coming to rest against the flange 119 in position for removal from the terminal.

A compression spring 133 normally urges the kick-off arms toward their outer position and this spring also serves to hold the 80 shoe 113 in its case-engaging position. Downward movement of the shoe is limited by the stops 134, on the arms 121.

The shoe 113, it will be noted, prevents 85 the powder case from bouncing off from the terminal shelf upon its arrival at the terminal and insures the delivery of the case by the kick-off mechanism at a definite point.

Having thus described my invention, what 90 I claim is:

1. In a pneumatic ammunition conveyer, a transmission tube provided with a dispatching terminal, a tube through which a charge, comprising a projectile of given dimensions and a mass of explosive material 95 of different size from said projectile, may be conveyed, and a delivery terminal having provisions for separating the projectile from said explosive material by said difference in size. 100

2. In a pneumatic ammunition conveyer, a transmission tube provided with a dispatching terminal, a tube through which a charge, comprising a projectile of given dimensions and a mass of explosive material 105 of different size from said projectile, may be conveyed, and a delivery terminal having provisions for separating the projectile from said explosive material by said difference in size, said separating provisions acting substantially independently of differences in weight of the parts separated. 110

3. In a pneumatic ammunition conveyer, a transmission tube provided with a dispatching terminal, a tube through which a charge, comprising a projectile of smaller 115 diameter than said tube and a cylindrical mass of explosive material of larger diameter than said projectile, may be conveyed, and a delivery terminal having provisions for separating the projectile from said explosive material by said difference in diameters thereof. 120

4. In a pneumatic ammunition conveyer, a transmission tube provided with a dispatching terminal, a tube through which a charge, comprising a projectile of smaller diameter than said tube and a cylindrical mass of explosive material of larger diameter than said projectile, may be conveyed, 125 130

and a delivery terminal having substantially staticinary provisions for separating the projectile from said explosive material by said difference in diameters thereof.

5 5. In a pneumatic ammunition conveyer, a transmission tube provided with a dispatching terminal, a tube through which a charge, comprising a projectile and a mass of explosive material, may be conveyed, a 10 pusher or piston, against which pneumatic pressure is exerted, to propel said charge through the tube, and a delivery terminal having bumpers for separately stopping the projectile and explosive material at different points in said terminal, said projectile traversing a longer path before encountering its bumper, after emerging from the tube, than said explosive material.

6. In a pneumatic ammunition conveyer, 20 a transmission tube provided with a dispatching terminal, a tube through which a charge, comprising a projectile and a mass of explosive material, may be conveyed, a pusher or piston, against which pneumatic pressure is exerted, to propel said charge through the tube, and a delivery terminal having bumpers for separately stopping the projectile and explosive material at different points in said terminal, said projectile traversing a longer path before encountering its bumper, after emerging from the tube, than said explosive material, said delivery terminal having a curved surface for swerving said projectile toward its bumper.

35 7. In a pneumatic ammunition conveyer, a transmission tube provided with a dispatching terminal, a tube through which a charge, comprising a projectile and a mass of explosive material, may be conveyed, a 40 pusher or piston, against which pneumatic pressure is exerted, to propel said charge through the tube, and a delivery terminal having bumpers at different levels for separately stopping the projectile and explosive 45 material, the bumper for said material being located above the path of said projectile through said terminal.

8. In a pneumatic ammunition conveyer, 50 a transmission tube provided with a dispatching terminal, a tube through which a charge, comprising a projectile and a mass of explosive material, may be conveyed, a pusher or piston, against which pneumatic pressure is exerted, to propel said charge 55 through the tube, and a delivery terminal having provisions for separating, according to size, the said projectile and mass of explosive material.

9. In a pneumatic ammunition conveyer, 60 a transmission tube provided with a dispatching terminal, a tube through which a charge, comprising a projectile and a mass of explosive material, may be conveyed, and a delivery terminal having a shelf of width 65 sufficient to permit of the emplacement

thereon of a plurality of charges and provisions for separating the component parts of said charges, whereby the projectiles may be collected upon one portion of said shelf and the explosive material on another portion thereof.

5 10. In a pneumatic ammunition conveyer, a transmission tube provided with a dispatching terminal, a tube through which a charge, comprising a projectile and a mass of explosive material, may be conveyed, and a delivery terminal having provisions for separately rolling the said parts of a charge out of the path of a succeeding charge.

11. In a pneumatic ammunition conveyer, 20 a transmission tube provided with a dispatching terminal, a tube through which a charge, comprising a projectile and a mass of explosive material, may be conveyed, and a delivery terminal having means for separately stopping the projectile and explosive material and provisions for automatically removing one at least of said parts of the charge from its stopping means.

12. In a pneumatic ammunition conveyer, 25 a transmission tube provided with a dispatching terminal, a tube through which a charge, comprising a projectile and a mass of explosive material, may be conveyed, and a delivery terminal having provisions for 30 swiveling one end of one of the parts of a charge laterally out of the path of the like part of a succeeding charge.

13. In a pneumatic ammunition conveyer, 35 a transmission tube provided with a dispatching terminal, a tube through which a charge, comprising a projectile and a mass of explosive material, may be conveyed, and a delivery terminal having provisions for 40 positioning side by side corresponding parts 45 of a plurality of charges successively delivered to said delivery terminal.

14. In a pneumatic ammunition conveyer, 50 a transmission tube provided with a dispatching terminal, a tube through which a charge, comprising a projectile and a mass of explosive material, may be conveyed, and a delivery terminal having provisions for 55 positioning side by side all corresponding parts of a plurality of charges successively 60 delivered to said delivery terminal.

15. In a pneumatic ammunition conveyer, 65 a transmission tube provided with a dispatching terminal, a tube through which a charge, comprising a projectile and a mass of explosive material, may be conveyed, and a delivery terminal having means for supporting the component parts of a plurality 70 of charges and provisions for assorting and disposing said parts separately upon said 75 supporting means.

16. In a pneumatic ammunition conveyer, 80 a transmission tube provided with a dispatching terminal, a tube through which a charge, comprising a projectile and a mass 85

of explosive material, may be conveyed, and a delivery terminal having means for supporting the component parts of a charge substantially out of the path of a succeeding charge and provisions for assorting said parts and separately disposing them upon said supporting means.

17. In a pneumatic ammunition conveyer, a transmission tube provided with a despatching terminal, a tube through which a charge, comprising a projectile and a mass of explosive material, may be conveyed, a delivery terminal adapted to separately arrest the component parts of said charge, means for creating a charge-transmitting flow of air through said tube, said tube having a bend therein, and means for reducing the speed of the charge when traversing said bend.
18. In a pneumatic ammunition conveyer, a transmission tube provided with a despatching terminal, a tube through which a charge, comprising a projectile and a mass of explosive material, may be conveyed, a delivery terminal adapted to separately arrest the component parts of said charge, means for creating a charge-transmitting flow of air through said tube, said tube having a bend therein, and means for reducing the speed of the charge when traversing said bend, said last mentioned means having provisions for regulating said speed.

19. In a pneumatic ammunition conveyer, a transmission tube provided with a despatching terminal, a tube through which a charge, comprising a projectile and a mass of explosive material, may be conveyed, a delivery terminal adapted to separately arrest the component parts of said charge, means for creating a charge transmitting flow of air through said tube, said tube having a bend therein, and means including a by-pass for reducing the speed of the charge when traversing said bend.

20. In a pneumatic ammunition conveyer, a delivery terminal adapted to receive and hold a plurality of charges each consisting of a projectile and explosive material therefor, a tube for conveying said charges to said delivery terminal, a despatching terminal for introducing charges into said tube, means for insuring a proper spacing of charges traversing said tube at the same time, and pushers distinct from said charges and adapted to be driven through said tube by air pressure, for propelling the charges.

21. In a pneumatic ammunition conveyer, a delivery terminal adapted to receive and hold portions at least of charges each consisting of a projectile and explosive material therefor, a tube for conveying said charges to said delivery terminal, a despatching terminal having a cover, means for actuating said cover, and means for controlling said cover-actuated means, said

controlling means being subject to the movement of a charge through said tube away from said despatching terminal and including an operative connection at a point along the length of the tube a determined distance 70 from said despatching terminal, said controlling means also having a locking part adapted to be moved into its unlocking position only after a despatched charge has passed said point.

22. In a pneumatic ammunition conveyer, a delivery terminal adapted to receive charges each consisting of a projectile and explosive material therefor, a tube for conveying said charges to said delivery terminal, a pusher 80 for propelling a charge through said tube and a despatching terminal having means for rendering it operative and provided with a part adapted for movement into the path of said pusher, said part when so positioned 85 being out of the path of the charge propelled by said pusher and adapted to prevent effective actuation of said means.

23. In a pneumatic ammunition conveyer, a delivery terminal adapted to receive 90 charges each consisting of a projectile and explosive material therefor, a tube for conveying said charges to said delivery terminal, a pusher for propelling a charge through said tube and a despatching terminal having means for rendering it operative and provided with a part adapted for movement into the path of said pusher, said part when so positioned being out of the path of the charge propelled by said pusher 100 and adapted to prevent effective actuation of said means, said means when operated co-acting with said part to position the latter in the path of the pusher preparatory to its displacement therefrom by said pusher. 105

24. In a pneumatic ammunition conveyer, a transmission tube, a despatching terminal therefor, a pusher for propelling charges through said tube ahead of said pusher, said charges being of less diameter than said 110 pusher, and means, a part of which is substantially in the path of said pusher while the latter is traversing said tube, for controlling said terminal to prevent a re-actuation thereof until said pusher reaches said 115 part, said charges being adapted to operatively clear said part, whereby the pusher alone actuates the latter.

25. In a pneumatic conveyer, a delivery terminal, a transmission tube normally 120 freely open at said delivery terminal, a despatching terminal having a cover and mechanism for closing the entrance to said tube separately from said cover, and controlling devices for said despatching terminal cover and tube closing mechanism, comprising means for preventing re-actuation of said mechanism after the entrance of a charge into said tube until said charge 125 has traversed a determined portion thereof, 130

said portion being less than the entire length of the tube, and said cover permitting of the emplacement of a second charge in said terminal while the first charge is traversing said portion of said tube.

5 26. In a pneumatic conveyer, a delivery terminal, a transmission tube through which a current of air normally flows, a despatching terminal having mechanism for directing said current of air therethrough for the despatch of a charge, and means for limiting the flow of said current of air through said despatching terminal to a substantially determined period of time after said charge 10 emerges therefrom, said current thereafter resuming its normal course.

27. In a pneumatic ammunition conveyer, a despatching terminal, a transmission tube, a source of low pressure air for propelling charges of ammunition through said tube, an operating mechanism for said terminal, a source of high pressure fluid for actuating said mechanism, and means for controlling said high pressure fluid and thereby said mechanism, said operating mechanism including a part, actuatable by said high pressure fluid, for controlling the flow of said low pressure air through said terminal.

28. In a pneumatic despatch apparatus, a despatching terminal, a transmission tube, and means for controlling the despatch of a body of material to be transmitted from said terminal, said means including mechanism for preventing the despatch of a succeeding body of material until the preceding material has traversed the transmission tube a determined distance, and auxiliary mechanism for preventing actuation of said means in any case until a charge being despatched 40 has left said terminal.

29. In a pneumatic despatch apparatus, a transmission tube, a despatching terminal having means for closing the entrance to said tube, mechanism for rendering said terminal operative for the despatch of a body of material to be transmitted through said tube and for inoperatively positioning said tube-closing means, said mechanism having provisions for preventing a re-actuation 45 thereof, after being once operated, until the despatch material has passed said tube-closing means, and means for preventing a re-actuation of said mechanism until after the lapse of a substantially determined period 50 subsequent to the despatch of a preceding body of material.

30. In a pneumatic despatch apparatus, a transmission tube, a despatching terminal having means for closing the entrance to 60 said tube, mechanism for rendering said terminal operative for the despatch of a body of material to be transmitted through said tube and for inoperatively positioning said tube-closing means, said mechanism having provisions for preventing a re-actuation 65

thereof, after being once operated, until the despatched material has passed said tube-closing means, and pneumatically controlled means for preventing a re-actuation of said mechanism until after the lapse of a substantially determined period subsequent to the despatch of a preceding body of material.

31. In a pneumatic despatch apparatus, a despatching terminal, a transmission tube, 70 mechanism for rendering said terminal operative for the despatch of material to be transmitted, controlling means for said mechanism, a transmitting member adapted to carry said material through said tube and 75 a locking device for said controlling means having operative connections with said tube and adapted to be rendered operative by the passage of said transmitting member past a determined point in said tube and to become inoperative after the passage of said member past a second point in said tube.

32. In a pneumatic despatch apparatus, a delivery terminal, a despatching terminal, a transmission tube connecting said terminals, mechanism for rendering said despatching terminal operative for the despatch of material, controlling means for said mechanism, a transmitting member adapted to carry said material through said tube, and 90 a latch for locking a part of said controlling means in position to maintain the parts of said despatching terminal in the positions into which they were moved when despatching said member, said latch adapted to be tripped by said transmitting member as the latter is propelled toward said delivery terminal.

33. In a pneumatic despatch apparatus, a transmission tube, a despatching terminal 95 therefor having a valve for controlling the flow of air through said terminal, a transmitting member adapted to carry material through said tube, and power actuated mechanism for controlling the movements of said valve, said mechanism having a controlling part, a plurality of locking members for said part and provisions for separately actuating said locking members by the passage of said transmitting member past successive 100 spaced points in said tube.

34. In a pneumatic despatch apparatus, a transmission tube, a despatching terminal having a cover and a gate adapted to close the entrance to said tube, mechanism for opening and closing said cover, said mechanism including toggle connections to said cover adapted to lock the same closed, and means for automatically opening said gate after said cover has been substantially closed 120 by its said connections.

35. In a pneumatic despatch apparatus, a transmission tube, a despatching terminal having a gate adapted to close the entrance to said tube, mechanism for opening said 130

- gate, a transmitting member adapted to carry material through said tube, means controlled by said member for setting said mechanism to close said gate, and means, 5 also controlled by said member, for normally preventing the re-opening of said gate by said mechanism until said member has traveled a determined distance through said tube.
- 10 36. In a pneumatic despatch apparatus, a transmission tube, a despatching terminal having a cover and a gate adapted to close the entrance to said tube, said cover being normally open and said gate closed, mechanism for closing said cover and opening said gate, a transmitting member adapted to carry material through said tube, and means controlled by said member for setting said mechanism to close said gate and re- 15 open said cover after the despatch of said member.
37. In a pneumatic despatch apparatus, a transmission tube, a despatching terminal having a cover and a gate adapted to close the entrance to said tube, said cover being normally open and said gate closed, mechanism for closing said cover and opening said gate, a transmitting member adapted 20
- to carry material through said tube, means controlled by said member for setting said mechanism to close said gate and re-open said cover after the despatch of said member, and means, also controlled by said member, for normally preventing the despatch of a second of said transmitting members 35 from said terminal until after the first member has traveled a determined distance through said tube.
38. In a pneumatic despatch apparatus, a despatching terminal, a transmission tube, power actuated mechanism for operatively displacing a part of said terminal for the despatch of carriers therefrom, said mechanism having a controlling part, means, operable by pneumatic pressure in a part of 40 said tube, for locking said controlling part against movement, and co-acting means, operable by pneumatic pressure in another part of said tube for releasing said controlling part. 45

In testimony whereof I have affixed my signature, in the presence of two witnesses.

JAMES T. COWLEY.
